UNITED STATES PATENT OFFICE.

HARRY VISSERING, OF CHICAGO, ILLINOIS.

TRIPLE SANDING APPARATUS.

1,275,108.

Specification of Letters Patent. Patented Aug. 6, 1918.

Application filed March 9, 1917. Serial No. 153,737.

To all whom it may concern:

Be it known that I, HARRY VISSERING, a citizen of the United States, and a resident of Chicago, in the county of Cook and State 5 of Illinois, have invented certain new and useful Improvements in Triple Sanding Apparatus, of which the following is a specification.

My present invention relates to sand-ejecting apparatus, more particularly to the track-sanding apparatus commonly used for applying sand adjacent the points of contact of the locomotive wheels with the rails, and has special reference to the provision of an 15 improved structure adapted to apply sand to a plurality of pairs of wheels of the locomotive.

The principal objects of my present invention are the provision of improved means of 20 applying sand to a plurality of pairs of wheels; the provision of means for supplying substantially equal amounts of sand to each of a plurality of pairs of wheels; the provision of means for supplying a plurality 25 of front sanders from a plurality of different parts of a sand receptacle, the provision of means for supplying front and rear sanders from the same part of a sand receptacle; the provision of improved means for 30 applying sand to the locomotive wheels, either by hand or by fluid pressure; the provision of improved means for applying sand in front of and in rear of a locomotive wheel; the provision of improved means for 35 controlling the amount of sand applied to the wheels; the provision of an improved form of controlling valve for operating the sanding apparatus, and generally, to improve track-sanding apparatus, together 40 with such further objects as may hereafter appear.

In attaining these and other objects and advantages to be hereinafter set forth, I have provided a construction one embodiment 45 of which is illustrated in the accompanying drawings, in which:—

Figure 1 is a diagrammatic side elevation of a locomotive with my improved sanding apparatus applied thereto;

Fig. 2 is a plan view of the sand trap; Fig. 3 is a side view of the sand trap;

Fig. 4 is a section on the line 4—4 of Fig. 2;

Fig. 5 is a section on the line 5—5 of Fig. 2;

Fig. 6 is a section through the cap valve on the line 6—6 of Fig. 7;

Fig. 7 is a section on the line 7—7 of Fig. 6; and

Fig. 8 is a side elevation of the distributor 60 bracket showing the manually operated valves.

The sanding apparatus is designed for both fluid pressure and manual operation, so that while the apparatus is normally 65 operated by fluid pressure it may still be operated when the source of fluid pressure fails. The fluid pressure operating means will be described first.

Referring to Fig. 1, which illustrates the 70 general arrangement of the sanding apparatus, 1 represents the sand box, 2 represents the sand trap operated by fluid pressure, usually compressed air, and 3, 4 and 5 the pipes leading to the wheels through which 75 the sand is supplied to the wheels.

The sand trap 2 is attached to the projecting base 64 of a distributor bracket 65 through which sand passes from the sand box to the trap and thence to the pipes 3, 80 4 and 5.

In the locomotive as shown, for purposes of illustration, there are five pairs of driving wheels coupled together, namely, 6, 7, 8, 9 and 10 the middle wheel 8 being connected 85 to the engine connecting rod and consequently driven directly by the engine. Sand is desirably supplied to both wheels 6 and 8 for the reason that if the drive be through the wheels 8 and sand were supplied to the 90 wheels 6 only, the other wheels, particularly wheel 8 being driven directly by the engine, not having material resistance to rotation when the track is slippery, would tend to turn at greater speed than the wheel 6 which 95 is driven only by the connecting rods between the wheels with the result that the latter connecting rod would become broken or strained.

Sand is preferably applied to the front 100 wheel in order to get the maximum tractive effort but at the same time sand should be

applied to the wheel driven directly by the engine.

One of the difficulties of track-sanding apparatus I have found is that it is difficult to supply sand in substantially equal amounts to both wheels 6 and 8. This difficulty is, however, overcome by means of the apparatus which I will now describe.

Sand from the sand box can pass through the distributor bracket 65 through four passages 66, 67, 68, and 69, of which passages 67 and 68 are normally closed by the manually operated valves 62 and 63. The several passages 66, 67, 68 and 69 register with the passages 20, 70, 71 and 21 in the sand trap. The angle of slope of the passages 67 and 68 (with their continuations 70 and 71) is greater than the angle of repose of sand so that sand will flow through them when not otherwise prevented. It will be seen by inspecting Figs. 2, 4 and 8 that if either of the valves 62 or 63 are lifted there will be a clear uninterrupted passage for sand to the pipes 3 or 4. On the other hand, although sand is free at all times to enter the passages 66 and 69 and their continuations 20 and 21, gravity flow of sand is prevented by the fact that the sand must pass through the upturned tubular parts 22 and 23 before reaching the passages leading to the sander pipes. These tubular parts 22 and 23 form part of the fluid ejecting means, illustrated more particularly in Figs. 2 to 5.

Inlet pipes 11, 12 and 13 are provided through which fluid under pressure, preferably compressed air, is passed to blow sand through the pipes 3, 4 and 5 respectively. The sand passes out of the trap by means of the threaded connections 14, 15 and 16 which are connected, respectively to the pipes 3, 4 and 5.

Referring now to Fig. 1, it will be seen that there are two compressed air pipes 17 and 11. The pipe 17 is connected to the branch pipes 12 and 13. When compressed air is passed through the pipe 17 sand is ejected through both pipes 4 and 5, and when compressed air is passed through the pipe 11, sand is ejected through the pipe 3 only.

The interior construction of the sand trap is shown more particularly in Figs. 4 and 5. Considering first the means for supplying sand to the pipes 4 and 5, it will be seen on reference to Fig. 4, that two sand ejecting devices are provided having jets 18 and 19 respectively, through which compressed air is blown in order to draw sand through the orifices 20 and 21, respectively, from the sand box 1. The sand is blown through the tubular parts 22 and 23 of the trap body which may be provided with lead linings 24 and 25 which will stand the abrasive action of the moving sand more successfully than steel or the other material of the trap body. The sand then strikes plugs 26 and 27, pro-

vided with lead inserts 28 and 29 whose function is the same as that of the sleeves 24 and 25. The sand is then carried by the air to the threaded connections 15 and 16, and from thence to the pipes 4 and 5. Plugs 30, 31, 32, etc., are provided for facilitating the cleaning of the trap from sand and other material which may have become lodged in the passages through which the compressed air is passed.

The construction of the means for supplying sand to the rear of the wheels by the pipe 3 is shown in Fig. 5, and as its construction is similar to that shown in Fig. 4 for the other pipes, there is no need to describe this construction further.

It will be noted however that the front and rear sanders 3 and 4 both take sand through the same orifice 20 leading to the same part of the sand receptacle. Although there is free communication between the passages leading to the front and rear sanders 3 and 4 the admittance of fluid under pressure into either pipe 11 or 12 produces a flow of sand toward one sander only. This is due to the fact that the compressed air or the like is introduced under pressure through a fine orifice and consequently at a considerable velocity which is sufficient to prevent the air exhausting through the wrong passage either entirely or at least sufficiently rapidly to draw sand with it. On the other hand sand for the two front sanders is taken from the different parts of the sand receptacle so that the pile of sand in the latter is reduced fairly uniformly as the rear sander is rarely used as compared with the front sanders. On account of the rarity with which the rear sander is used and on account of the normally much lower speed on reverse than on forward movement, only one rear sander is used this being placed to operate on the wheel directly coupled to the engine.

My improved sanding device is applicable to existing sand domes or boxes for sanding apparatus with no change in the parts other than the addition of the novel form of sand trap distributor bracket and the connections thereto.

In Figs. 6 and 7 a valve is shown for controlling the supply of compressed air, or other fluid, to the sand trap. This valve consists of a body 33, having conical seating 34 therein for the conical valve 35. The valve 35 is held pressed against the valve seat 34 by means of the action of the spring 36, and also by reason of the fact that the high-pressure side of the valve is on the same side of the valve as the spring 36 so that the valve is pressed against its seat by fluid pressure as well as by spring pressure. A suitable connection 37 to a source of fluid pressure is provided and a suitable closing member 38 is arranged to screw into the body 33 of the valve and hold the spring 36.

in position. The valve 35 is rotated by means of the handle 39 which is provided with a spring-held latch 40, operated by the spring 41. The inner end of this latch 40 is rounded at 42 so that while normally holding the valve in any desired position by reason of the engagement of this rounded end with one of the rounded recesses 43 in the body of the valve 33, the valve handle 10 can be readily moved by hand into any desired position. The handle 37 is mounted on a squared end 44 on the shank 45 of the valve 35. A bolt 46 and a washer 47 are provided for holding the handle 37 in position 15 on this squared portion 44.

In order to adjust the amount of sand delivered by the sanding apparatus provision is made for supplying varying amounts of compressed air, and for this purpose I have 20 provided in the valve 35 three ports of graduated sizes—48, 49 and 50 for the rear sander, and three graduated ports 51, 52 and 53 for the front sander. The ports in the valve body 33 are arranged so as to uncover first one and then the other of these ports so that the amount of air can be progressively increased or decreased as desired.

The ports 51, 52 and 53 are made substantially larger, preferably twice as large as the ports 48, 49 and 50 as there is only one rear sander while there are two front sanders.

The rounded recesses 43 are arranged so 35 that as the latch is moved into successive recesses the ports 48, 49 and 50 on the one hand and the ports 51, 52 and 53 on the other are successively brought into register with their corresponding port in the body 40 of the valve.

An alarm device 50 is provided for indicating when the sander is in operation and thus avoiding depletion of the sand supply as the result of forgetting to take the sander 45 out of operation as soon as its need has passed.

For operating the sander manually in case the supply of compressed air, or other fluid pressure, fails, I have provided means for 50 manually operating the sander. For this purpose two rods 54, 55 are arranged to lead from the cab to the levers 56 and 57 in the sand box. Suitable knobs or handles 58 and 59 are provided on the cab end of these rods 55 to facilitate their manipulation. The levers 56 and 57 are arranged to lift the rods 60 and 61 respectively to which are connected the valve members 62 and 63 (see Fig. 8). If the valve 62 be lifted, sand flows by gravity 60 through the passages 67 and 70 leading to the rear sander pipe 3. If the valve 63 be lifted sand flows by gravity through the passages 68 and 71 leading to the front sander pipe 4.

65 As the manual means of operation are

only used when the supply of compressed air fails only one rear and one front sander is operated manually. These sanders are those adapted to supply sand to the wheel directly coupled to the engine.

Having thus described my invention and illustrated its use what I claim as new and desire to secure by Letters Patent is:

1. A track sanding apparatus comprising in combination a receptacle for sand, manually operated means for discharging material from said sand receptacle at will either in front of or behind the path of movement of a wheel, fluid pressure means for ejecting material from said sand receptacle at will for directing sand to either the front or rear of the wheel, the said ejecting means being adapted for distributing the sand in front of a plurality of wheels on one side independently of the other side of a locomotive.

2. A track sanding apparatus comprising in combination a single sand trap, two sand passages within said trap, means for discharging sand from said passages to two points of a series of wheels and means for discharging sand from one of said passages alternately to a third point in said series.

3. A track sanding apparatus comprising in combination a receptacle for sand, front and rear sanders, a sand trap having three passages therein, manual means for discharging sand directly from said receptacle through two of said passages, and fluid pressure means for ejecting sand from the third passage into either of the other two passages.

4. A track sanding apparatus comprising in combination a receptacle for sand, front and rear sanders, and manual and fluid pressure means for discharging sand through either the rear sanders or a plurality of the front sanders and a connection whereby the sand for one of the front sanders may be withdrawn from the source of supply of the rear sander.

5. A locomotive track sanding apparatus comprising in combination a sand trap, a rear sander and a plurality of front sanders on one side of a locomotive and fluid pressure means for discharging sand through either the rear sander or a plurality of front sanders.

6. A track sanding apparatus comprising, in combination, a receptacle for sand, a plurality of pairs of front sanders, one pair in front of the leading pair of driving wheels and another pair in front of the pair of driving wheels directly connected to the cylinder connecting rods, a pair of rear sanders for said last mentioned pair of wheels, fluid pressure means for discharging sand through either the pair of rear sanders or the plurality of pairs of front sanders and manual means for discharging sand.

sand through either front or rear sanders for said last mentioned pair of wheels.

7. A track sanding apparatus comprising in combination a receptacle for sand, fluid pressure means for discharging sand from said receptacle, and a valve for controlling the flow of fluid under pressure having two sets of graduated ports adapted to give varying amounts of fluid, said sets being of different sizes.

8. A track sanding apparatus comprising in combination a rear sander, a plurality of front sanders and a sand trap having a single sand passage therein for said rear sander and one of said front sanders.

9. A track sanding apparatus comprising in combination, a rear sander, a plurality of front sanders and a sand trap having a single passage for said rear sander and one of said front sanders and fluid pressure means for ejecting sand from said source into said rear and front sanders.

10. A track sanding apparatus comprising in combination a sand trap having connections to a plurality of sanders, a source of fluid pressure, and two fluid pressure ports in continuous open communication with said connections for ejecting sand from a single mass of sand in one part of the trap in two different directions.

11. A track sanding apparatus comprising in combination, a receptacle for sand, a rear sander and a plurality of front sanders, and means for ejecting sand from one part of said receptacle to either said rear sander or one of said front sanders.

12. A track sanding apparatus comprising in combination a receptacle for sand, a rear sander and a plurality of front sanders, and means for ejecting sand from one part of said receptacle to either said rear sander or one of said front sanders and means for ejecting sand from another part of said receptacle into another of said front sanders.

13. A track sanding apparatus comprising in combination a receptacle for sand, a sander pipe, two passages between said receptacle and said pipe, one of said passages having an inclination not less than the natural angle of rest for sand throughout its entire length and the other of said passages having two branch passages, each having an inclination greater than the natural angle of rest for sand for a part of their length, a valve for closing said first mentioned passage and means for propelling sand through one or other of the branches of the other of said passages.

14. A track sanding apparatus comprising in combination a receptacle for sand, a sander pipe, two passages between said receptacle and said pipe, one of said passages having an inclination not less than the natural angle of rest for sand throughout its entire length and the other of said passages

having two branch passages, each having an inclination greater than the natural angle of rest for sand for a part of their length, means for interrupting the passage of sand through said first mentioned passage and means for propelling sand through one or other of the branches of the other of said passages.

15. A track sanding apparatus comprising, in combination, a receptacle for sand, two sander pipes, three passages for establishing communication between said receptacle and said pipes, two of said passages having an inclination not less than the natural angle of rest for sand throughout its entire length, and the other of said passages having two branch passages each having an inclination greater than the natural angles of rest for a part of their length, means for interrupting the passage of sand through said first-mentioned passages, and means for propelling sand through one or the other of the branches of the other of said passages.

16. A track sanding apparatus comprising, in combination, a receptacle for sand, manually operated means for discharging material from said sand receptacle at will either in front of or behind the path of movement of a wheel, fluid pressure means for ejecting material from said sand receptacle at will for directing sand to either the front or rear of the wheels, the said ejecting means being adapted for distributing the sand in front of the path of movement of a plurality of wheels on each side of a locomotive.

17. A locomotive track sanding apparatus comprising in combination, a receptacle for sand, a rear sander and a plurality of front sanders on one side of a locomotive, and manual means for discharging sand through either the one type of said sanders or the other type of said sanders, and fluid pressure means for discharging sand through either the one type of said sanders or a plurality of the other type of said sanders.

18. A track sanding apparatus comprising, in combination, a receptacle for sand, front and rear sanders, and manual and fluid pressure means for discharging sand through either the one type of said sanders or a plurality of the other type of said sanders, and a connection whereby the sand for one type of said sanders may be withdrawn from the source of supply of the other type of said sanders.

19. A track sanding apparatus comprising, in combination, a sand trap having fewer sand passages leading thereto than sand discharge pipes leading therefrom, front and rear sanders, and fluid pressure means for discharging sand through either one type of said sanders or a plurality of the other type of said sanders.

20. A track sanding apparatus comprising, in combination, a plurality of sanders including front and rear types, and a stationary sand trap having a single passage in permanent connection with one of said rear sanders and one of said front sanders.

21. A track sanding apparatus comprising, in combination, a plurality of sanders including front and rear types, and a stationary sand trap for one of said rear sanders and one of said front sanders, and fluid pressure stationary means for ejecting sand from a single passage in said trap into said rear sander and into said front sander alternately.

22. A track sanding apparatus comprising, in combination, a stationary sand distributer trap, a plurality of sanders including rear and front types, and fluid pressure means for ejecting sand from a mass of sand in one part of said distributer to either a rear sander or a front sander.

23. A track sanding apparatus comprising in combination, a rear sander, a plurality of front sanders, a sand trap and means for discharging sand from different points along a single passage in said trap into said rear sander and one of said front sanders.

24. A track sanding apparatus comprising in combination, a rear sander, a plurality of front sanders, a sand trap and fluid pressure means for discharging sand from different points along a single passage in said trap into said rear sander and one of said front sanders.

25. A track sanding apparatus comprising, in combination, a plurality of sanders including front and rear types, and a single source of sand for one of said rear sanders and one of said front sanders, and a second source of sand for another of said front sanders.

26. A track sanding apparatus comprising in combination, a plurality of sanders including front and rear types, and a single source of sand for one of said rear sanders and one of said front sanders and a second source of sand for another of said front sanders, and fluid pressure means for ejecting sand from said source into said rear sander and into said front sanders alternately.

27. A track sanding apparatus comprising, in combination, a receptacle for sand, a plurality of sanders including rear and front types, and means for ejecting sand from one part of said receptacle to either a rear sander or a front sander, and means for ejecting sand from another part of said receptacle to another front sander.

28. A track sanding apparatus comprising in combination, a sand trap having a plurality of sand passages therein, a rear sander and a plurality of front sanders, and means for discharging sand from one of said

passages into said rear sander or one of said front sanders alternatively, and means for discharging sand from another of said passages into another of said front sanders.

29. A track sanding apparatus comprising in combination a sand distributer trap, a rear sander, a front sander and means for ejecting sand from a mass of sand in one part of said distributer to either said rear sander or said front sander.

30. A track sanding apparatus comprising in combination, a sand trap, a plurality of pairs of front sanders, one pair in front of the leading pair of driving wheels and another pair in front of the pair of driving wheels directly connected to the cylinder connecting rods, a pair of rear sanders for said last-mentioned pair of wheels and fluid pressure means for discharging sand through either the pair of rear sanders or the plurality of pairs of front sanders.

31. A track sanding apparatus comprising in combination, a sand trap, a plurality of pairs of front sanders, one pair in front of the leading pair of driving wheels and another pair in front of the pair of driving wheels directly connected to the cylinder connecting rods, a pair of rear sanders for said last-mentioned pair of wheels and means for discharging sand through either the pair of rear sanders or the plurality of pairs of front sanders.

32. A track sanding apparatus comprising in combination, a sand trap, a source of fluid pressure, and two fluid pressure ports in said trap for ejecting sand from different points along a single passage in said trap in two different directions.

33. A track sanding apparatus comprising in combination a single sand trap, inclined sanders leading therefrom, for discharging sand from said trap to two points of a series of wheels and alternately to a third point only of said series.

34. A track sanding apparatus comprising in combination, a rear sander, a plurality of front sanders, and a sand trap having a single sand passage for said rear sander and one of said front sanders and a second sand passage for another of said front sanders, said sanders being inclined throughout substantially their entire length.

35. A track sanding apparatus comprising in combination, a rear sander, a plurality of front sanders and a sand trap having a single sand passage for said rear sander and one of said front sanders and fluid pressure means for ejecting sand from said passage alternately into said rear and front sanders, said sanders being inclined throughout substantially their entire length.

36. In a track sanding apparatus, a sand trap comprising a casing having connections to a rear sander, to a plurality of front sanders, and to means for ejecting sand

from one part of said trap to either said rear sander or to one of said front sanders.

37. In a track sanding apparatus, a sand trap comprising a casing having connections 5 to a rear sander, to a plurality of front sanders, and to means for ejecting sand from one part of said trap to either said rear sander or to one of said front sanders, and to means for ejecting sand from another 10 part of said trap into another of said front sanders.

38. In a track sanding apparatus, a sand trap comprising a casing having connections 15 to a rear sander, to a plurality of front sanders, and to an ejecting means, said casing having a single passage in communication with both said rear-sander connection and with one of said front sander connections for discharging sand thereinto from 20 different points along said passage.

39. A track sanding apparatus comprising, in combination, a receptacle for sand, a plurality of sanders including rear and front types, and stationary means for ejecting sand 25 from one part of said receptacle to either a rear sander or a front sander, said sanders being inclined throughout substantially their entire length.

40. A track sanding apparatus comprising 30 in combination a receptacle for sand, front and rear sanders, a sand trap having three passages therein connected to the said

receptacle, front and rear sanders respectively, and fluid pressure means for ejecting sand from the first passage into either of the 35 other passages.

41. A track sanding apparatus comprising in combination a sand trap, a plurality of pairs of front sanders, one pair in front of the leading pair of driving wheels and another pair in front of the pair of driving wheels directly connected to the cylinder connecting rods, a pair of rear sanders for 40 said last-mentioned pair of wheels and fluid pressure means for discharging sand through either the pair of rear sanders or the plurality of pairs of front sanders, said sanders being inclined throughout substantially their entire length.

42. In a track sanding apparatus, a sand trap comprising a casing having connections 45 to a rear sander, to a plurality of front sanders and to sand ejecting means, said casing having a single source of sand for said rear sander and one of said front sanders, and a second source of sand for another of said front sanders.

In testimony whereof I have hereunto signed my name in the presence of the two subscribing witnesses.

HARRY VISSERING.
